UNITED STATES PATENT OFFICE.

ALBERT J. H. KUHSIEK, OF RICHMOND HILL, NEW YORK, ASSIGNOR TO EDWARD V.
HARTFORD, INC., A CORPORATION OF NEW YORK.

JACK.

Application filed January 31, 1918. Serial No. 214,595.

To all whom it may concern:

Be it known that I, ALBERT J. H. KUHSIEK, a citizen of the United States, residing at Richmond Hill, county of Queens, 5 and State of New York, have invented certain new and useful Improvements in Jacks, of which the following is a specification.

This invention relates to jacks in general and more particularly to jacks for vehicles 10 such as automobiles and the like.

The principal object of my present invention is to provide a jack in which the operating mechanism for the lifting member may be positioned by a mere reciprocation of 15 the handle so that the lifting member may be either raised or lowered as desired.

Another object of my invention is to provide a jack in which the lifting member is engageable by a plurality of pawls whenever it is raised or lowered.

A further object of my invention is to provide a jack in which the opposite sides of the lifting member are engageable by pawls, one of which is always under the control of 25 the operating means for changing the position of the load, and the other of which is arranged to hold the load when the operating means is not being manipulated, and to arrange the operating means and the last 30 mentioned pawl so that that pawl may be relieved of the load whenever it is desired to lower the lifting member.

These and other features, capabilities and advantages of this invention will appear 35 from the subjoined detailed description of one specific embodiment thereof illustrated in the accompanying drawings.

Figure 1 is a side elevation of a jack made in accordance with the present invention.

Figure 2 is an end elevation with parts thereof shown in section.

Fig. 3 is an enlarged fragmental view, partly in section of the active parts of the jack in position to raise the lifting member.

Fig. 4 is a section on the line IV-IV of Fig. 3 showing the parts in position to raise the lifting member.

Fig. 5 is a section similar to that shown in Fig. 4 with the parts in position to lower 50 the lifting member.

Fig. 6 is an enlarged fragmentary view partly in section showing the active parts in position to lower the lifting member.

Fig. 7 is another enlarged fragmentary view showing the parts in position to lower 55 the lifting member with the lever depressed.

Fig. 8 is still another enlarged fragmentary view showing the parts in position to lower the lifting member with the lever in its intermediate position.

In the embodiment shown there is provided a standard 10 having a centrally located passageway 11 therein for the reception of the vertically slidable lifting member 12 which is illustrated as having a load 65 receiving shoulder 13 at its upper end with a lateral extension 14 forming an auxiliary load carrying element.

For properly guiding the lifting member or rack bar 12, the interior of the standard 70 10 is provided with two opposing guide rails 20 to accommodate the grooves 21 of the lifting member. At the upper end of the standard 10 there is an enlargement or housing 15 having a bearing at the lower 75 portion of the open side thereof for mounting an upwardly extending retaining pawl 16 to co-operate with the toothed side 17 of the lifting member 12. Extending through the open side of the enlargement 15, and 80 rearwardly on either side of the lifting member 12 to the closed side of the enlargement 15 are the bifurcations of the rockable operating member or lever 19, such bifurcations 18 being provided with pivots 22 in the 85 form of studs which are disposed in the horizontal slots or guideways 23 in the walls of the enlargement 15. The slots 23 in the present instance are sufficiently long to permit the studs 22 to travel a distance equal 90 substantially to their own length. To resiliently retain the studs in either of two positions, one preferably at one end of the slot and the other at the other end, resilient members such as the clamping springs 24 95 are provided one on each side wall of the enlargement 15. The clamping springs 24 are bifurcated to provide jaws having two anchoring or retaining portions corresponding to the two positions aforesaid. The right 100 hand end of the bifurcations 18, as viewed in the drawing, are provided with a shaft 25 on which the lifting pawl 26 is mounted with its upper active end adapted to co-operate with the toothed side 27 of the lifting member 12.

5 The pawl 26 is provided with a pin 28 co-operating with the flat cushion spring 29 positioned on the upper surface of one of the bifurcations 18, and also with a spring 10 30 engaging the pin 28 at one end, having a portion coiled around the shaft 25 and its other end secured to the side of one of the bifurcations 18, the spring 30 normally maintaining the pin 28 in engagement with the spring 29.

15 The pawl 16 is also provided with a spring 31 for normally maintaining it in engagement with the toothed side 17 of the lifting member 12, the spring 31 having one end 15 engaging the back of the pawl 16, and a portion thereof coiled around the shaft 32 forming the bearing for the pawl 16, and its other end secured to one side of the enlargement 15.

20 The pawl 16 is also provided with a pin 33 adapted to co-operate with the spring 34 which is fixed at one end to the operating member 19, and has its other end extending obliquely downwardly and formed into a 25 finger for engagement with the pin 33.

The operating member 19 is preferably of the usual socketed type to receive an elongated handle portion 35.

30 The operation of the device is substantially as follows: When the studs 22 are disposed in the front position, that is, remote from the closed side of the enlargement 15, the pawl 26 will be set and the pawl 16 will be controlled to raise the lifting member 35 when actuated; the pawl 26 on the downward movement of the lever 19 first engaging the lifting member 12 when the operating member 19 is substantially in a horizontal position. In this position of the 40 pawl 26, the pawl 16 will always engage the lifting member 12 both when the operating member 19 is raised or lowered, thus always 45 in position to instantaneously grasp the lifting member 12 when any part of the load is being withdrawn from the pawl 26 as when the operating member 19 is raised to give the pawl 26 a fresh grip.

On the other hand when the lever 19 is bodily moved so that the studs 22 are in 50 their rear position that is near the closed side of the enlargement 15, the timing of the pawls 16 and 26 in their gripping action will be such as to permit the lifting member 12 to descend.

55 By means of the co-operation of the spring 34 with the pin 33, the pawl 16 will be held out of engagement with the lifting member 12 in the downward movement of the operating member 19, and only permitted to 60 engage the lifting member 12 on the upward movement of the operating member 19 that is when the pawl 26 is withdrawn from engagement with the lifting member 12, the timing of the engagements of the pawls 16 65 and 26 with the lifting member 12 being

such that the lifting member 12 will be permitted to descend a tooth-space whenever the pawl 26 is withdrawn and the load is taken up by the pawl 16.

It is obvious that various changes and 70 modifications may be made to the details of construction without departing from the general spirit of the invention.

I claim:

1. A toothed lifting jack having a standard, a lifting member mounted in said standard, mechanism cooperating with the teeth on the lifting member for moving the lifting member upward or downward, said mechanism also including an operating 80 member, a handle bar associated with said operating member, said operating member being longitudinally and bodily movable to assume a position where it will raise the lifting member or lower the lifting member 85 as desired.

2. In a jack, a standard, a toothed lifting member mounted in the standard, and means cooperating with the teeth on the lifting member for raising or lowering the lifting member, said means including pawl mechanism and an operating member slidably mounted in the standard to have two operating 90 positions, in one of which positions repeated manipulation of the operating member lowers the lifting member step by step, and the other position, repeated manipulation 95 raises the lifting member step by step.

3. In a jack, a standard, a toothed lifting member mounted in the standard, means co-operating with the teeth on the lifting member for raising or lowering the lifting member, said means including pawl mechanism and an operating member slidably mounted in the standard to have two operating 100 positions, in one of which positions repeated manipulation of the operating member lowers the lifting member step by step; and the other position, repeated manipulation 105 raises the lifting member step by step, and means 110 to releasably retain the operating member in one or the other of said positions.

4. In a jack, a standard, a toothed lifting member mounted in the standard, two pawls co-operating with said toothed lifting member, an operating member slidably mounted in the standard, and means carried by the operating member to control the sequence of engagement of the pawls and lifting member whereby the lifting member may be 120 raised or lowered by manipulation of the operating member.

5. In a jack, a standard, a toothed lifting member mounted in the standard, two pawls co-operating with said toothed lifting member, an operating member slidably mounted in the standard, and means carried by the operating member and responsive solely to the position thereof, to control the sequence 125 of engagement of the pawls and lifting 130 member.

- in member whereby the lifting member may be raised or lowered by manipulation of the operating member.
6. In a jack, a standard, a lifting member mounted in the standard, means for raising or lowering the lifting member, said means including a pivoted operating member slidably mounted to have operating positions on two different axes, and means to releasably retain the operating member in one or the other of said positions.
7. In a jack, a standard, a lifting member mounted in the standard, means for raising or lowering the lifting member, said means including a slidably mounted operating member having two operating positions, and bifurcated spring means to releasably retain the operating member in one or the other of said positions.
8. In a jack, a standard having slots therein, a lifting member slidably mounted in said standard; pivots in said slots; an operating member mounted on the pivots, movable to slide the pivots in the slots; means operatively connecting the operating member to said lifting member; a handle bar for said operating member; and a spring member having jaws to retain said pivots in one position whereby said operating member may be operated to raise said lifting member and in another position whereby said operating member may be operated to lower said lifting member.
9. In a jack; a standard having slots therein; a lifting member slidably mounted in said standard; an operating member having pivots in said slots; means operatively connecting the operating member to said lifting member, said operating member being longitudinally movable to slide the pivots in the slots; and means to retain said pivots in one position whereby said operating member may be operated to raise said lifting member and in another position whereby said operating member may be operated to lower said lifting member.
10. In a lifting jack; a standard having a slotted enlarged portion near the upper end thereof; a lifting member slidably mounted in said standard and having two toothed portions; a pawl pivotally mounted at one side of said enlarged portion; means for normally maintaining said pawl in engagement with one toothed portion of said lifting member; a longitudinally slideable operating member having bifurcations, one on either side of said lifting member, said bifurcations being pivotally mounted in the slots in said enlarged portion near the other side thereof; a second pawl pivotally supported by said bifurcations near said other side of said enlarged portion and adapted to engage the other toothed portion of the lifting member, said second pawl having a pin adjacent the upper surface of one of said bifurcations; means for normally maintaining said pin in such relation and said second named pawl in engagement with the
- furcations; means for normally maintaining said pin in such relation and said second pawl in engagement with the lifting member; a second pin on said first named pawl; and a spring on said operating member, said operating member being longitudinally slideable to permit the last mentioned spring to co-operate with the second named pin in one position of the operating member to lower the lifting member, and slideable to another position to raise the lifting member.
11. In a lifting jack; a standard having a slotted enlarged portion near the upper end thereof; a lifting member slidably mounted in said standard and having two toothed portions; a pawl pivotally mounted at one side of said enlarged portion; means for normally maintaining said pawl in engagement with one toothed portion of said lifting member; a longitudinally slideable operating member having bifurcations, one on either side of said lifting member, said bifurcations being pivotally mounted in the slots in said enlarged portion near the other side thereof, a cushion spring on one of the bifurcations; a second pawl pivotally supported by said bifurcations near said other side of said enlarged portion and adapted to engage the other toothed portion of the lifting member, said second pawl having a pin adjacent the cushion spring on one of said bifurcations; means for normally maintaining said pin in such relation and said second pawl in engagement with the lifting member; a second pin on said first named pawl; and a spring on said operating member, said operating member being longitudinally slideable to permit the last mentioned spring to co-operate with the second named pin in one position of the operating member to lower the lifting member, and slideable to another position to raise the lifting member.
12. In a lifting jack; a standard having a slotted enlarged portion near the upper end thereof; a lifting member slidably mounted in said standard and having two toothed portions; a pawl pivotally mounted at one side of said enlarged portion; means for normally maintaining said pawl in engagement with one toothed portion of said lifting member; a longitudinally slideable operating member having bifurcations, one on either side of said lifting member, each of said bifurcations having an outstanding stud mounted in the slots in said enlarged portion near the other side thereof; a second pawl pivotally supported by said bifurcations near said other side of said enlarged portion and adapted to engage the other toothed portion of the lifting member, said second pawl having a pin adjacent the upper surface of one of said bifurcations; means for normally maintaining said pin in such relation and said second named pawl in engagement with the

- lifting member; a second pin on said first named pawl; and a spring on said operating member, said operating member being longitudinally slidable to permit the last mentioned spring to co-operate with the second named pin in one position of the operating member to lower the lifting member, and slidable to another position to raise the lifting member.
13. In a lifting jack; a standard having a slotted enlarged portion at the upper end thereof, said portion being open at one side and closed at the other side; a lifting member slidably mounted in said standard and having two toothed portions; a pawl pivotally mounted near the open side of said enlarged portion; means for normally maintaining said pawl in engagement with one toothed portion of said lifting member; a longitudinally slidable operating member extending outwardly through said open side and having bifurcations, one on either side of said lifting member, said bifurcations being pivotally mounted in slots in said enlarged portion near the closed side thereof; a second pawl pivotally supported by said bifurcations near the closed side of said enlarged portion and adapted to engage the other toothed portion of the lifting member; said second pawl having a pin adjacent the upper surface of one of said bifurcations; means for normally maintaining said pin in such relation and said second named pawl in engagement with the lifting member; a second pin on said first named pawl; and a spring on said operating member, said operating member being longitudinally slidable to permit the last mentioned spring to co-operate with the second named pin in one position of the operating member to lower the lifting member, and slidable to another position to raise the lifting member.
14. In a jack; a standard having slots therein, a lifting member carried by said standard, an operating member mounted in said slots for both rectilinear movement along the slots and oscillatory movement about selected positions in the slots, means for operating the lifting member from the operating member, and means for retaining said operating member in such selected positions in said slots whereby it may be manipulated to raise or to lower said lifting member according to the position selected.
15. In a jack, a standard, a lifting member, a series of ratchet teeth on two opposite sides of the lifting member, an operating member pivoted in the standard and means interposed between the operating member and lifting member and associated with the standard to raise or to lower the lifting member step by step, said means comprising two pawls, one engageable with one set of ratchet teeth, and the other pawl engageable with the other set of ratchet teeth, and means

regulated by the operating member for controlling the sequence of such engagement upon successive movements of the operating member.

16. In a jack, a standard, a lifting member having two series of ratchet teeth, a slidably pivotally mounted operating lever, a lifting pawl pivotally carried by the operating lever and co-operative with one series of teeth, a retaining pawl carried by the standard, means urging the retaining pawl toward the other series of teeth, and means carried solely by the operating lever and responsive to its position for overcoming the urging means and disengaging the retaining pawl from the teeth when a load is on the lifting pawl and the lever is in the position for lowering the load, said last mentioned means becoming ineffective when the operating lever is moved to its extreme position while lowering the load.

17. In a jack; a lifting bar; a standard provided with bearings; an operating member mounted for bodily movement along the bearings into either one of two operative positions and for pivotal movement about the bearings; and means, associated with said member and controlled by the bodily movement thereof, for raising the bar while the member, in one operative position, is oscillated, and for lowering the bar while the member, in another operative position, is oscillated, said means including means whereby the thrust produced by the load being moved by the lifting bar is transmitted through the bearings to the standard.

18. In a jack; a lifting bar; a standard provided with bearings; an operating member mounted for bodily movement along the bearings into either one of two operative positions and for pivotal movement about the bearings; and means, associated with said member and controlled by the bodily movement thereof, for raising the bar with step by step movement, while the member, in one operative position, is oscillated, and for lowering the bar with a step by step movement, while the member, in another operative position, is oscillated, said means including means whereby the thrust produced by the load being moved by the lifting bar is transmitted through the bearings to the standard.

19. In a jack, a rack bar, a pawl normally in engagement with said bar, a retaining dog normally in engagement with the bar, means for reciprocating said pawl, said means being movable into either one of two operative positions relative to said dog, and means for moving the dog out of engagement with the bar and releasing it and subsequently moving the pawl out of engagement with said bar when said reciprocating means is in one of its operative positions, said means moving the pawl out of engagement with the bar during its down stroke when the reciprocating

ing means is in said position so as to permit step by step lowering of the bar.

20. In a jack, a rack bar, a standard having bearings, a pivoted rockable member, a pawl normally in engagement with said bar, connections between said pawl and member for reciprocating the pawl, a retaining dog normally in engagement with said bar, the member being mounted in said bearings to be bodily adjustable into either one of two operative positions relative to said dog, means actuated by the member when in one position for moving the dog into inoperative position and releasing it, and means for moving the pawl out of engagement with the rack bar during its downward stroke subsequent to release of the dog.

21. In a jack, a rack bar, a rockable shaft, a pawl supported by said shaft so as to be reciprocated thereby and normally in engagement with said bar, a retaining dog normally in engagement with the bar, the shaft being adjustable into either one of two operative positions relative to the dog, means for preventing engagement of said pawl with the bar until the pawl approaches the limit of its upward travel and for moving the pawl out of engagement with the bar as it moves downwardly when the shaft is in one position, and means for moving the dog out of engagement with said bar and holding it in this position during downward travel of the pawl and then releasing said dog prior to movement of the pawl out of engagement with said bar, when the shaft is in said position.

22. In a jack, a rack bar, a retaining dog normally in engagement with said bar, an operating shaft adjustable into either one of two operative positions relative to said dog, a pawl carried by said shaft so as to be reciprocated thereby and normally in engagement with the bar, means for preventing engagement of said pawl with the bar until the pawl approaches the limit of its up stroke and for moving said pawl out of engagement with the bar during its down stroke when the shaft is in one position, and means actuated by operation of the shaft for moving the dog out of engagement with the bar and for releasing it immediately prior to movement of the pawl out of engagement with the bar when the shaft is in said position to permit step by step lowering of said bar.

23. A mechanism for actuating the lifting member of a jack, comprising an operating member having bifurcations adapted to accommodate the lifting member, outwardly projecting pivot means carried by each bifurcation, a shaft spanning the bifurcations near their outer ends, a pawl on the shaft, a spring intermediate the pawl and one of the bifurcations for urging the pawl in one direction, and a slotted support to accommodate the pivot means whereby the op-

erating member may be moved transversely of the lifting member.

24. A mechanism for actuating the lifting member of a jack, comprising an operating member having bifurcations adapted to accommodate the lifting member, a pivot means carried by each bifurcation, a shaft spanning the bifurcations near their outer ends, a pawl on the shaft, a spring intermediate the pawl and one of the bifurcations for urging the pawl in one direction, and a cushion spring carried by one of the bifurcations for limiting the movement of the pawl in the same direction.

25. In a jack, a standard, a toothed lifting member mounted in the standard, a pawl pivoted with respect to the standard and urged against the toothed lifting member by a spring, an operating member slidably mounted in the standard to have two operating positions, and a device carried by the operating member which, when said member is in one of its operating positions, actuates the pawl away from the lifting member, and which is automatically rendered non-functioning by movement of the operating member to the other operating position.

26. In a jack, a standard, a toothed lifting member mounted in the standard, a pawl pivoted with respect to the standard and urged against the toothed lifting member by a spring, an operating member slidably mounted in the standard above the pawl to have two operating positions and an obliquely downwardly extending member carried by the operating member which, when said member is in one of its operating positions, actuates the pawl away from the lifting member.

27. In a jack, a standard having vertical guideways for a lifting member, substantially horizontal guideways at one side of the vertical guideways for the pivots of a shiftable, rockable operating member, and bearings at the opposite side of the vertical guideways for a retaining pawl.

28. In a jack, a standard having upper and lower vertical guideways for a lifting member and a housing intermediate the upper and the lower guideways, said housing being provided with walls spaced a greater distance apart than the guideways whereby to provide spaces between the walls and interposed lifting member, horizontal guideways in the walls at one side of the vertical guideways for the pivots of a shiftable, rockable, operating member and bearings on the opposite side of the vertical guideways for a retaining pawl.

29. In a jack, a standard having a housing for the operating mechanism and provided with spaced apart walls each having a horizontal slot adapted to pivotally support a pivot member in a plurality of positions, and

15 a resilient member mounted on one horizontal wall and extending alongside one slot, said resilient member having two anchoring portions to embrace the pivot and hold it in either of two operating positions.

16 30. In a jack, a lifting bar, a standard provided with bearings, a pivoted operating member mounted in the bearings to be bodily adjustable into either one of two operative 20 positions, and means associated with said member and controlled by the adjustment thereof for raising the bar when the member is in one position and lowering the bar when said member is in its other position, said means including a pawl normally 25 in engagement with the bar, the pawl being supported on the operating member.

26 31. In a jack, a lifting bar, a standard provided with bearings, a pivoted operating member mounted in the bearings to be bodily adjustable into either one of two operative 30 positions, and means associated with said member and controlled by the adjustment thereof for raising the bar with a step by step movement when the member is in one position and lowering the bar when said member is in its other position, said means including a pawl normally in engagement 35 with the bar, the pawl being supported on the operating member.

35 32. In a jack, a rack bar, a pivoted rockable member, a pawl normally in engagement with said bar, interconnections between said pawl and member for reciprocating the pawl 40 and supporting the pawl from the member, a retaining dog normally in engagement with said bar, the member being bodily adjustable into either one of two operative positions relative to said dog, means actuated 45 by the member when in one position for moving the dog into inoperative position and releasing it, and means for moving the pawl out of engagement with the rack bar during its downward stroke subsequent to release of the dog.

46 33. In a jack, a lifting bar, a standard provided with bearings, a pivoted operating

member mounted in the bearings to be bodily adjustable into either one of two operative positions, and means associated with said member and controlled by the adjustment thereof for raising the bar when the member is in one position and lowering the bar when said member is in its other position, the axis of the operating member 50 being stationary when the lifting bar is being raised or lowered.

34. In a jack, a lifting bar, a standard provided with bearings, a pivoted operating member mounted in the bearings to be bodily 60 adjustable into either one of two operative positions, and means associated with said member and controlled by the adjustment thereof for raising the bar with a step by step movement when the member is in one 65 position and lowering the bar when said member is in its other position, the axis of the operating member being stationary when the lifting bar is being raised or lowered.

35. In a jack, a lifting bar, an operating 70 shaft adjustable into either one of two operative positions, and means associated with said shaft and controlled by the adjustment thereof for raising the bar when the shaft is in one position and lowering the bar when 75 said shaft is in its other position, the axis of the operating shaft being transversely shifted for such adjustment and being stationary when the lifting bar is being raised or lowered.

80 36. In a jack, a lifting bar, an operating shaft adjustable into either one of two operative positions, and means associated with said shaft and controlled by the adjustment thereof for raising the bar with a step 85 by step movement when the shaft is in one position and lowering the bar when said shaft is in its other position, the axis of the operating shaft being transversely shifted for such adjustment and being stationary 90 when the lifting bar is being raised or lowered.

ALBERT J. H. KUHSIEK.
